UNITED STATES PATENT OFFICE.

WILLIAM F. KRICHBAUM, OF NEWARK, NEW JERSEY, ASSIGNOR OF ONE-HALF TO D. LEWIS DALRYMPLE, OF NEWARK, NEW JERSEY.

PRESSURE-CONTROLLING DEVICE.

No. 797,440.

Specification of Letters Patent.

Patented Aug. 15, 1905.

Application filed April 3, 1905. Serial No. 253,704.

To all whom it may concern:

Be it known that I, WILLIAM F. KRICHBAUM, a citizen of the United States, residing at Newark, in the county of Essex and State of New Jersey, have invented certain new and useful Improvements in Pressure-Controlling Devices; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to that class of automatic pressure-controlling devices which are operated by the high or initial pressure acting upon a piston which actuates a main valve to open the same, the admission of said high or initial pressure to said piston being controlled by an auxiliary or secondary valve, which in turn is operated by a diaphragm subject to any variations from the pressure desired to be maintained.

The objects of the invention are to provide such a pressure-controlling device which can be used, first, as a pump-governor adapted to admit to a pumping-engine an operating pressure which shall be under the control of the pump-discharge pressure; second, as a blower-valve or fan-engine controller adapted to maintain a uniform boiler-pressure by transmitting variations therein to the blower or fan-engine, and, third, as a pressure-regulator or reducing-valve to provide such a pressure-controlling device which is of simple construction; to secure in such a device an auxiliary valve which shall operate downward against the flow of the high pressure to the main-valve-controlling piston; to provide a recess around the said auxiliary-valve seat which shall afford an ample steam-space at that point; to obtain a construction having a spring and adjusting-nut arranged intermediate of the diaphragm and the auxiliary-valve seat; to conveniently center said spring; to provide a by-pass adapted to be used in connection with the employment of the device as a blower-valve, and to secure other advantages and results, some of which may be hereinafter referred to in connection with the description of the working parts.

The invention consists in the improved pressure-controlling device and in the ar-

rangements and combinations of parts of the same, all substantially as will be hereinafter set forth, and finally embraced in the clauses of the claim.

Referring to the accompanying drawings, in which like figures of reference indicate corresponding parts in each of the several figures, Figure 1 is an elevation of my improved device looking lengthwise of the pipe to which it is applied and being partly in section, as on line α , Fig. 3. Fig. 2 is a central section of the device on a plane at right angles to that of Fig. 1, and Fig. 3 is a view from beneath of a certain top piece adapted to be mounted upon the body portion proper of the device.

In said drawings, 2 indicates the body portion of the valve, apertured and threaded at one end 3 to receive a high-pressure-supply pipe and at its other end 4 to receive a continuation of said pipe beyond the valve. Between its said ends the body portion 2 has a partition 5, as is common in globe-valves, and in said partition is an aperture 6, forming at its under side a horizontal seat for a valve 7. Said valve 7 has a stem which extends both upwardly and downwardly, the lower portion 8 being surrounded by a coiled spring 9, which supports the weight of the valve. The upper portion 10 of the stem extends through the top of the valve-chamber proper and carries a piston 11, arranged in a piston-cylinder 12, which is preferably formed integral with the valve-body 2 and separated therefrom by the partition 30. Into the top of said piston-cylinder 12 screws a top piece 13, which is apertured at its upper part to receive the auxiliary valve 14, the lower portion of said aperture being enlarged, as at 15, and providing a valve-seat 16 at the lower part. From said valve-seat 16 an aperture or passage 31 leads through the top piece 13 to an annular recess 17 near the lower outer edges of the same, and which annular recess connects with a passage 18, leading upward from the valve-body 2 on the inlet side of the valve 7. A further passage 19 leads from the enlarged chamber 15 at one side of the valve-seat 16 therein down through the top piece 13 into the piston-chamber 12. It will be thus understood that when the auxiliary valve 14 is lifted the high pressure admitted at the inlet end 3 will pass upward through passages 18, 17, and 31 into chamber 15 and downward through passage 19 to act upon the piston 11, and this pis-

ton being of larger area than the valve 7 will be forced downward to open said valve 7, so that the high pressure thus passes directly through the valve-body 2.

The upper part of the top piece 13 is threaded, as at 20, to receive a frame 21, which forms at its upper end a chamber 22 for a flexible diaphragm 23, the top of said chamber being closed by a cap 24, apertured and threaded, as at 25, to receive a pipe connection. The auxiliary valve 14 abuts at its upper end 26 against the diaphragm 23, and thus as said diaphragm is lowered or raised by the pressure above it said auxiliary valve 14 is operated. A spiral spring 27 beneath the head 26 of the auxiliary valve serves to regulate the operation of the same, and a collar 28 below said spring is threaded to screw in a transverse seat 29 of the frame 21 to regulate the power of the spring. By the construction thus described it will be understood that when pressure upon the diaphragm 23 is sufficiently strong it will force the auxiliary valve 14 downward and so close the high-pressure passage at the valve-seat 16. This shuts off passage of high pressure to the upper side of the piston 11 and permits the closing of the valve 7 under the direct flow of said high pressure.

In using my improved device as a pump-governor the pump-discharge is connected as at 25, and thus the admission of the steam or other pressure fluid to the pump-engine is regulated by the discharge. When employed as a blower-valve, the initial pressure which enters the valve-body 3 is connected to the diaphragm at 25, and thus as the pressure gets too high the valve closes against the passage of pressure fluid to the fan or blower, which creates the boiler draft, thus cooling down the boiler. To prevent the blower stopping entirely, I prefer to provide in the valve wall or partition 5 an aperture 32, adapted to be entirely or partially closed by a screw 33 and which aperture may be left permanently open to permit sufficient pressure to pass to keep the blower-engine in motion. As a pressure-regulator the outlet end 4 of the valve-body 2 is connected to the diaphragm, as well as to the place of supply, and thus reduces the pressure supplied to any desired point.

Having thus described the invention, what I claim as new is—

1. In a pressure-controlling device, a body portion having inlet and outlet ends with a partition between providing a valve-seat and a piston-cylinder at the top of said body part, a main valve for said valve-seat having a stem with a piston thereon lying in said cylinder, a top piece closing the top of said piston-cylinder and having a chamber therein with a passage leading therefrom into the piston-cylinder, the said body portion and top piece providing a passage from the inlet end of the body portion opening into said chamber and

said chamber providing a valve-seat, an auxiliary valve projecting into said chamber and being adapted to engage said seat to close communication between the said passages, a flexible diaphragm adapted to engage the other end of said auxiliary valve, and a cap forming with said diaphragm a closed pressure-space and providing means for connecting a duct or pipe.

2. In a pressure-controlling device, a body portion having inlet and outlet ends with a partition between providing a valve-seat and a piston-cylinder at the top of said body part, a main valve for said valve-seat having a stem with a piston thereon lying in said cylinder, a top piece closing the top of said piston-cylinder and having a chamber therein with a floor having a raised portion and a passage leading from said chamber into the piston-cylinder, the said body portion and top piece providing a passage leading from the inlet end of the body portion into the said chamber, one of the said passages opening into said chamber through the said raised portion of the chamber-floor, an auxiliary valve projecting through the top of said top piece to engage said raised portion of the chamber-floor as a valve-seat, a flexible diaphragm adapted to engage the other end of said auxiliary valve, and a cap forming with said diaphragm a closed pressure-space and providing means for connecting a duct or pipe.

3. In a pressure-controlling device, a body portion having inlet and outlet ends with a partition between providing a valve-seat and a piston-cylinder at the top of said body part, a main valve for said valve-seat having a stem with a piston thereon lying in said cylinder, a top piece closing the top of said piston-cylinder and having a chamber therein with a floor having a horizontal portion and a passage leading from said chamber into the piston-cylinder, the said body portion and top piece providing a passage leading from the inlet end of the valve into the chamber, one of said passages opening into said chamber through the said horizontal portion of the chamber-floor and forming a horizontal valve-seat, an auxiliary valve projecting downward into the said chamber to engage the said valve-seat, a flexible diaphragm adapted to engage the other end of said auxiliary valve, and a cap forming with said diaphragm a closed pressure-space and providing means for connecting a duct or pipe.

4. In a pressure-controlling device, a body portion having a piston-cylinder at its upper side, a main valve in said body portion having a piston-head lying in said cylinder, a top piece providing an auxiliary-valve space with passages leading therefrom to the piston-cylinder and inlet end of the body portion respectively, a frame open at its sides mounted upon said top piece, a diaphragm at the top of said frame, a cap above said diaphragm,

and an auxiliary valve mounted in said frame with its upper end against the said diaphragm and its lower end adapted to close communication between the said passages opening into the top-piece chamber.

5. In a pressure-controlling device, a body portion having a piston-cylinder at its upper side, a main valve in said body portion having a piston-head lying in said cylinder, a top piece providing an auxiliary-valve space with passages leading therefrom to the piston-cylinder and inlet end of the body portion respectively, a frame open at its sides mounted upon said top piece, a diaphragm at the top of said frame, an auxiliary valve mounted in said frame with its upper end against the said diaphragm and its lower end adapted to close communication between the said passages opening into the top-piece chamber, a coiled spring upon said auxiliary valve below the diaphragm, and an adjusting-nut mounted in the frame below said spring.

6. In a pressure-controlling device, a body portion having a piston-cylinder at its upper side, a main valve in said body portion having a piston-head lying in said cylinder, a top piece providing an auxiliary-valve space with passages leading therefrom to the piston-cylinder and inlet end of the body portion respectively, a frame open at its sides mounted upon said top piece, a diaphragm at the top of said frame, an auxiliary valve having a head engaging the said diaphragm and a reduced shank extending downward and adapt-

ed at its lower end to close communication between the said top-piece passages, an adjusting-nut mounted in the frame between the diaphragm and top piece and loosely surrounding the shank of the auxiliary valve, annular centering projections upon facing sides of said adjusting-nut and the auxiliary-valve head, and a spiral spring upon said projections between the said parts.

7. In a blower-controlling valve, a body portion having inlet and outlet ends with a partition between providing in itself a valve-seat and a by-pass or aperture independent of the valve-opening, said body portion also having a piston-cylinder at its top, a main valve for said valve-seat having a stem with a piston thereon lying in said cylinder, an auxiliary valve adapted to control the passage of initial pressure through said inlet end of the body portion to the said piston, a diaphragm adapted to be exposed to said initial pressure and to transmit movement to said auxiliary valve, and a regulating-screw for said by-pass, whereby the blower-engine may be prevented from stopping entirely and yet governed by the controlling-valve.

In testimony that I claim the foregoing I have hereunto set my hand this 20th day of March, 1905.

WILLIAM F. KRICHBAUM.
